CLAIM

The ornamental design for a stud for the sole of a shoe, as shown and described.

DESCRIPTION

FIG. 1 is a perspective view of the bottom and one side of a stud for the sole of a shoe showing my new design;

FIG. 2 is a bottom plan view thereof;

FIG. 3 is a top plan view thereof;

FIG. 4 is a first side elevational view thereof;

FIG. 5 is a second side elevational view opposite the first side elevational view thereof;

FIG. 6 is a third side elevational view thereof;

FIG. 7 is a fourth side elevational view opposite the third side elevational view thereof; and,

FIG. 8 is a diametrical sectional view thereof, taken along line 8—8 of FIG. 2.
